UNITED STATES PATENT OFFICE.

CLAIR H. ELLIOTT AND ARTHUR SUPANSICK, OF SAN DIEGO, CALIFORNIA, ASSIGNEES
OF ONE-THIRD TO EDWARD LOOS, OF SAN DIEGO, CALIFORNIA.

DESIGN FOR AN ELECTRIC-LAMP STAND.

58,898.

Specification for Design.

Patented Sept. 6, 1921.

Application filed January 13, 1921. Serial No. 437,104. Term of patent 7 years.

To all whom it may concern:

Be it known that we, CLAIR H. ELLIOTT and ARTHUR SUPANSICK, citizens of the United States, residing at San Diego, in the county of San Diego and State of California, have invented a certain new, original, and ornamental Design for Electric-Lamp Stands, of which the following is a specification, reference being had to the accompanying drawing, forming a part thereof.

The figure is an elevational view showing an electric lamp stand with my new design.

We claim:

The ornamental design for an electric lamp stand as shown.

In testimony whereof we have hereunto set our hands at San Diego, California, this 4th day of January, 1921.

CLAIR H. ELLIOTT.
ARTHUR SUPANSICK.
